UNITED STATES PATENT OFFICE.

JOSEPH W. HOODWIN, OF CHICAGO, ILLINOIS.

CRIMPING MACHINE.

Application filed April 20, 1920. Serial No. 375,228.

To all whom it may concern:

Be it known that I, JOSEPH W. HOODWIN, a citizen of the United States, and a resident of Chicago, in the county of Cook and State 5 of Illinois, have invented new and useful Improvements in Crimping Machines, of which the following is a specification.

My invention relates to an improved crimping machine, designed particularly for 10 crimping longitudinally strips of paper which have been perforated transversely so that the crimped strips may be compactly folded and separated along the perforation 15 lines into pellets which can be readily inserted into pockets formed in boards or other devices.

In prior machines such crimping is accomplished by passing the strips between crimping rolls. This method of crimping 20 has disadvantages which my improved machine overcomes. In my machine, the blank strips are laid over a row of grooves and die members then successively brought against the strip to successively depress sections thereof into the grooves, the sequence 25 of operation of the dies being such that the strip will not be torn but will be accurately crimped without strain.

A machine incorporating the various features of my invention is shown on the accompanying drawings, in which—

Fig. 1 is a plan view,

Fig. 2 is an elevational view of the left side of the machine,

Fig. 3 is an enlarged sectional view on plane 3—3, Fig. 1,

Fig. 4 is a sectional view on plane 4—4, Fig. 3,

Fig. 5 is a sectional view on plane 5—5, Fig. 4, and

Fig. 6 is a perspective view of a length of the finished crimped product.

The supporting structure for my improved machine, comprises the bed plate 10 mounted on legs 11. On the bed plate is supported the crimping die block 12 by means of the side walls 13 and 14. The die block has in its top a row of crimping grooves 15, extending from left to right and being here 50 shown of V-shape. In front of the die block is the feed shelf 16, partly supported by the die block and partly by the legs 17 resting on the bed plate 10.

Behind the die block and parallel with the 55 crimping grooves is the cam shaft 18 which at its ends is journaled in the bearing

frames 19 and 20, rising from the bed plate 10. At its right end the shaft carries the gear wheel 21 which is engaged by the driving pinion 22. A bracket 23 supported on the bed plate 10 supports the shaft 24 which at its inner end journals the pinion 22 together with the grooved collar 25. The pulley 26 is also mounted on the shaft and is adapted for connection by a belt (not shown) with a suitable driving source. The pulley has frictional engagement with the collar 25 and the collar is normally locked against rotation by the engagement of the tooth 27 with the projection 28 on the collar, the tooth being formed on the lever 29 hinged at its rear end on bracket 30 on the bed plate 10. A link 31 connects the lever at its front end with the foot pedal 32 hinged on the shaft 33 extending between the rear legs of the supporting structure. The foot pedal and lever 29 are normally held up by means of the compression spring 34 interposed between the lever 29 and the bed plate 10 (Fig. 1). In this position the tooth 27 is held in the path of the projection 28 and the cam shaft cannot be rotated. When the foot lever is depressed, the tooth will be withdrawn and the pinion 22 will be free to rotate the gear 21 and the cam 85 shaft.

Overhanging the die block 12 at the sides thereof, are the L shaped guide frames 35 and 36 which at their rear ends receive the shaft 18. These frames have in their front 90 ends the rectangular vertically extending guide spaces 37 and 38 for guiding the die plates 39. These die plates are arranged in a horizontal row within the guide spaces and their lower ends are V shaped to fit the respective V shaped grooves 15 in the die block 12.

Outside of the frames 35 and 36 the shaft 18 is of reduced diameter to provide the shoulders 40 and 41. Mounted on the shaft 100 and secured against the shoulder 40 by the nut 42 is the row of cams 43, there being as many cams as there are die plates. At the other end of the shaft a row of cams 44 is secured against the shoulder 41 by the nut 45. Extending to the left from the frame 35 is the bracket 46 between whose depending outer end and the frame is secured the pivot screw 47. On this screw are hinged the cam levers 48 which extend 110 rearwardly from the respective die plates 39 and in the path of the respective cams 43.

The frame 36 has a similar bracket 49 supporting the pin 50 on which are hinged the cam levers 51 which extend rearwardly from the right ends of the respective die plates 39 and over the respective cams 44. Suspended from the rear end of each lever by means of a cord 52 is a weight 53, these weights tending to hold the cam levers against their respective cams.

10 The corresponding arms of the levers 48 and 51 have the forwardly extending tongues 54 and 55 which extend respectively into the notches or openings 56 and 57 at the ends of the respective die plates. With this arrangement, the cam arms and die plates can be very readily assembled in place on the machine. Each die plate has preferably the extension 58 which is V-shaped to fit the die block grooves.

20 In Fig. 3 the shape and arrangement of the cams is clearly shown. The cams are in the form of disks which are cylindrical except for a cam hump or projection *h* whose outer surface is cylindrical with its center at the axis of the cam shaft. The cam disks are off-set circumferentially a sufficient distance so that the cam humps will engage successively with the cam arms, the off-set of the cams 44 being the same as that for the cams 30 43 so that two cam groups raise their respective cam arms to cause the die plates to shift vertically with uniformity. The inner cam arms of the sets connect with the ends of the rear die plate, while the outer arms connect 35 with the front die plate. The off-set arrangement of the cams is such that the inner cams are in advance, rotation being in the direction indicated on Fig. 3. During each rotation of the cam shaft, the die plates are 40 thus raised successively beginning with the rear plate and ending with the front plate, the cam off-set being sufficient to cause each die plate to engage fully in its corresponding die groove before the next plate is 45 brought into its groove.

Figs. 1 and 2 show a paper blank strip *S* positioned on the table 16 against the guide bracket 59, ready to be inserted into the machine. The strip is shifted rearwardly over the die grooves 15 and into the under cut spaces or notches 60 formed at the bases of the frames 35 and 36. The operator then steps on the pedal lever and releases the driving mechanism whereupon the cam shaft 50 rotates, the die plates then successively engaging in the die grooves 15. First the rear die plate comes down and carries the paper over the rear notch into the notch and pulls it. When the plate is fully in the notch to 60 hold the paper, the next die plate engages the paper and draws it down into the next notch and so on until the front plate has carried the paper into the corresponding groove. During each engagement of a plate 65 in a groove, the paper is drawn transversely

rearwardly to supply stock for filling the grooves. The notches 60 permit sufficient overlap of paper so that the rear groove will be fully filled when the rear plate enters it. In order to retain the crimped and folded form of the strip the die plate 12 is preferably heated, a pipe 61 being shown below the die plate supplying gas to burners 62. The frames 35 and 36 at their front ends have laterally extending wings 63 for assisting in properly guiding the die plates. Where the die plates are long, a center frame 64, similar to frames 35 and 36, may be provided as shown, to receive the die plates at their centers.

80 Ejector mechanism is provided for ejecting crimped strips from the die grooves. Extending from the bed plate 10 are the inner and outer posts 65 and 66 for guiding the rod 67, the posts being provided with top plates 68 and 69 respectively, for holding the rod in the grooved tops of the posts. At its inner end, the rod terminates in a head 70 having the V-shaped tongues 71 for engaging in the die grooves 15. Between the posts 55 and 56 the rod is received by a clamping block 72 held thereon by means of a set-screw 73. Pivoted at its rear end on the bed plate 10 is the cam lever 74 which has a cam lug 75 engaging in the cam groove 76 of the cam 77 mounted on the left hand of the shaft 18. At its front end the cam lever has the pin 78 which extends into the opening 79 of the clamp 72. Normally, the co-operation of the cam 77 with the cam lever 76 causes it to hold the rod 67 in its extreme position to the left and with its head 70 at the left side of the die block out of range of the die plates. After the die plates 39 have been operated to crimp a strip and have been removed from the die block 12, the deflected section 76' of the cam groove 76 co-operates with the cam lug to swing the cam lever 74 to the right to cause the rod 67 to shift its head 70 through and along the die grooves 15, the projections 71 on the head encountering the crimped strip and shifting it toward the right from the die block and on to the chute 80. After the ejector mechanism has been restored to normal position, the operator releases the pedal lever to stop the machine or she can quickly insert another blank strip into the machine for the next crimping operation.

110 Fig. 6 shows the finished crimped strip. The paper blanks may be transversely perforated along lines 81 as indicated in Fig. 1 and the various transverse sections provided with numbers or other information giving legends. After the strip has then 115 been crimped longitudinally, to the form shown in Fig. 6, it can be fully compressed transversely along the crimped lines and separated into pellets by tearing along the perforation lines 81. The pellets or informa- 120 125 130

tion bearing sections are thus very compact and can be readily inserted in small openings or pockets.

I thus provide a very simple, durable and efficient machine for crimping paper strips. I do not, of course, desire to be limited to the precise construction, arrangement and operation shown and described as changes can no doubt be made without departing from the scope of the invention.

I claim as follows:

1. In a crimping machine, the combination of a die block having a row of die grooves therein, guide frames above said grooves, a row of die plates supported by and reciprocable in said frames toward and away from said grooves, a set of cam levers connected with each end of said plates, a cam shaft, two sets of cams on said shaft for said sets of cam levers, the cams of the sets being correspondingly circumferentially off-set whereby during rotation of said shaft said levers will be reciprocated to apply said plates successively in said grooves. 70
2. In a crimping machine of the class described, the combination of a die block having a plurality of crimping grooves therein, a plurality of die plates for co-operating with said grooves, guide frames for supporting said plates, a cam shaft, two sets of cams on said shaft, similarly circumferentially off-set, two sets of cam arms co-operating respectively with said sets of cams, the arms of each set having connection at their ends with the respective ends of said die plates whereby during co-operation of said cams with said arms, said plates will be reciprocated and brought into operative association with said grooves to crimp material placed over said grooves. 75
3. In a crimping machine of the class described, the combination of a die block having a plurality of crimping grooves therein, guide frames over said block, a row of die plates vertically reciprocable in said frames toward and away from said grooves, a set of cam levers for each end of said row of plates, the respective arms of each set having pivotal engagement with the end of the respective plates, a cam shaft, a set of cams for each set of arms on said shaft, the cams of said sets being correspondingly circumferentially off-set whereby during rotation of said shaft said arms will be successively swung and said plates successively vertically reciprocated and brought successively into engagement with their respective cam grooves, to crimp material placed between said grooves and plates. 80
4. In a crimping machine of the class described, the combination of a die block having a row of crimping grooves therein, guide frames over said grooves, a row of die plates supported by and guided by said frames, a bracket extending laterally from each guide frame behind the respective end of said row of plates, a set of cam arms pivoted on each bracket and vertically reciprocable in said frames toward and away from said grooves, a set of cam arms extending rearwardly from each end of said row of plates, the arms of each set having tongue and groove connection with the respective ends of said plates, a cam shaft, a set of cams for each set of arms on said shaft, the cams of said sets being correspondingly circumferentially off-set whereby upon rotation of said shaft the respective arms of said sets will be swung to cause successive reciprocation of said plates into successive engagement in said grooves. 85
5. In a crimping machine of the class described, the combination of a die block having a plurality of crimping grooves therein, a row of die plates, means for supporting said plates for reciprocation toward and away from said grooves, means for successively reciprocating said plates to bring them successively into said grooves whereby material placed over said grooves will be crimped, ejector mechanism, and means for shifting said ejector mechanism across said block after a crimping operation to remove the crimped product from said grooves. 90
6. In a crimping machine of the class described, the combination of a die block having a row of crimping grooves therein, a row of die plates over said grooves, frames for supporting said plates, means for shifting said plates successively into said grooves to crimp material placed over said grooves, an ejector head having a number of projections for engaging in said grooves, and means for shifting said ejector head with its projections through said grooves to eject the finished crimped product from said grooves and die block. 95
7. In a crimping machine, the combination of a die block having a row of crimping grooves therein, supporting frames over said grooves, a row of die plates reciprocable in said frames toward and away from said grooves, a cam shaft, cams on said shaft, cam arms extending from said plates into the paths of said cams, said cams being arranged to co-operate with said arms to cause successive engagement of said plates in said grooves whereby to crimp material placed over said grooves, an ejector head, a cam on said cam shaft, and a cam arm co-operating with said cam and connected with said ejector head to cause reciprocation of said head over said block to eject therefrom a finished crimped product. 100
8. In a crimping machine, the combination of a die block having a row of crimping grooves therein, guide frames mounted over said grooves, a row of die plates supported by and guided by said frames, a bracket extending laterally from each guide frame behind the respective end of said row of plates, a set of cam arms pivoted on each bracket and 105
9. In a crimping machine, the combination of a die block having a row of crimping grooves therein, guide frames over said grooves, a row of die plates supported by and guided by said frames, a bracket extending laterally from each guide frame behind the respective end of said row of plates, a set of cam arms pivoted on each bracket and 110
10. In a crimping machine, the combination of a die block having a row of crimping grooves therein, guide frames over said grooves, a row of die plates supported by and guided by said frames, a bracket extending laterally from each guide frame behind the respective end of said row of plates, a set of cam arms pivoted on each bracket and 115
11. In a crimping machine, the combination of a die block having a row of crimping grooves therein, guide frames over said grooves, a row of die plates supported by and guided by said frames, a bracket extending laterally from each guide frame behind the respective end of said row of plates, a set of cam arms pivoted on each bracket and 120
12. In a crimping machine, the combination of a die block having a row of crimping grooves therein, guide frames over said grooves, a row of die plates supported by and guided by said frames, a bracket extending laterally from each guide frame behind the respective end of said row of plates, a set of cam arms pivoted on each bracket and 125
13. In a crimping machine, the combination of a die block having a row of crimping grooves therein, guide frames over said grooves, a row of die plates supported by and guided by said frames, a bracket extending laterally from each guide frame behind the respective end of said row of plates, a set of cam arms pivoted on each bracket and 130

having pivotal connection at its front end with the ends of the respective plates, a cam shaft, a set of cams on said shaft for each set of arms, the cams of the sets being correspondingly circumferentially off-set whereby said arms will be swung in sequence when the shaft is rotated, such sequential operation of the arms causing reciprocation of said die plates into successive engagement 5 in said die grooves whereby to crimp material placed over said grooves.

9. In a crimping machine, the combination of a die block having a row of crimping grooves therein, guide frames mounted over 15 said grooves, a row of die plates supported by and guided by said frames, a bracket extending laterally from each guide frame behind the respective end of said row of plates, a set of cam arms pivoted on each bracket 20 and having pivotal connection at its front end with the ends of the respective plates, a cam shaft, a set of cams on said shaft for each set of arms, the cams of the sets being correspondingly circumferentially off-set 25 whereby said arms will be swung into se-

quence when the shaft is rotated, such sequential operation of the arms causing reciprocation of said die plates into successive engagement in said die grooves whereby to crimp material placed over said grooves, 30 and ejector mechanism operable after a crimping operation to eject the finished crimped product from the machine.

10. In a crimping machine, the combination of a die block having a row of crimping 35 grooves therein, guide frames over said block, a row of die plates reciprocable in said frames toward and away from said grooves, a cam shaft, a pair of cams for each plate on said shaft, and a pair of arms supporting each plate, said arms being arranged in the paths of the respective pairs of cams. cooperation of said cams with said cam arms 40 causing said die plates to be positively shifted into said die grooves, whereby paper 45 placed over said grooves will be crimped.

In witness whereof, I hereunto subscribe my name this 7th day of April, A. D. 1920.

JOSEPH W. HOODWIN.
